US0D1000468S

(12) **United States Design Patent** (10) **Patent No.:** **US D1,000,468 S**
(45) **Date of Patent:** **** Oct. 3, 2023**

(54) **DISPLAY SCREEN OR PORTION THEREOF
WITH GRAPHICAL USER INTERFACE**

(71) Applicants: **YOKOGAWA ELECTRIC
CORPORATION**, Musashino (JP);
**YOKOGAWA TEST &
MEASUREMENT CORPORATION**,
Musashino (JP)

(72) Inventors: **Ayako Kouno**, Musashino (JP);
Daisuke Sato, Tokyo (JP); **Yang Feng**,
Tokyo (JP); **Gentarou Ishihara**, Tokyo
(JP)

(73) Assignees: **YOKOGAWA ELECTRIC
CORPORATION**, Tokyo (JP);
**YOKOGAWA TEST &
MEASUREMENT CORPORATION**,
Tokyo (JP)

(**) Term: **15 Years**

(21) Appl. No.: **29/850,322**

(22) Filed: **Aug. 18, 2022**

Related U.S. Application Data

(62) Division of application No. 35/512,016, filed on Dec. 10, 2020 (U.S. filing date under 35 U.S.C. 384), and having an international filing date of Dec. 10, 2020.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing our new design.

The peripheral dashed broken lines illustrate a display screen or portion thereof, and form no part of the claimed design.
